UNITED STATES PATENT OFFICE

JOHN ARCHIBALD ARMSTRONG, OF CHICAGO, ILLINOIS, ASSIGNOR TO THE HERMAN NELSON CORPORATION, OF MOLINE, ILLINOIS, A CORPORATION OF ILLINOIS

DESIGN FOR A GRILLE

Application filed April 21, 1930. Serial No. 35,332. Term of patent 14 years.

To all whom it may concern:

Be it known that I, JOHN ARCHIBALD ARMSTRONG, a citizen of the United States, residing at Chicago, in the county of Cook and State of Illinois, have invented a new, original, and ornamental Design for Grille, of which the following is a specification, reference being had to the accompanying drawing, forming part of this specification.

In the drawing, the figure is a face view of a grille showing my new design. The grille, as a whole, is substantially flat.

I claim:

The ornamental design for a grille, as shown and described.

JOHN ARCHIBALD ARMSTRONG.
